PLATE OR SIMILAR ARTICLE

Ann F. Landau, Beverly Hills, Calif., assignor to Wallace China Co., Ltd., Los Angeles, Calif., a corporation of California

Application May 26, 1958, Serial No. 51,070

Term of patent 14 years

(Cl. D44—15)

The figure is a top view of a plate or similar article, showing my new design.

The shape of the plate is of a conventional configuration as viewed from the edge thereof.

I claim:

The ornamental design for a plate or similar article, substantially as shown and described.
